UNITED STATES PATENT OFFICE.

WILLIAM R. JEAVONS, OF CLEVELAND, OHIO.

DESIGN FOR A STOVE-DRUM.

45,007.

Specification for Design.

Patented Dec. 9, 1913.

Application filed August 12, 1911. Serial No. 643,806. Term of patent 7 years.

To all whom it may concern:

Be it known that I, WILLIAM R. JEAVONS, a citizen of the United States, residing at Cleveland, in the county of Cuyahoga and State of Ohio, have invented a new, original, and ornamental Design for Stove-Drums, of which the following is a specification, reference being had to the accompanying drawing, forming part thereof, wherein the figure

illustrates in elevation a stove-drum, showing my new design.

I claim:—

The ornamental design for a stove drum, as shown.

WILLIAM R. JEAVONS.

Witnesses:

J. B. HULL,
BRENNAN B. WEST.
